Des. 215,114
Patented Sept. 2, 1969

215,114

COMBINED COASTER AND ASH TRAY

Richard B. Cronheim, 7 Upper Barnes,
St. Louis, Mo. 63124

Filed Dec. 9, 1968, Ser. No. 14,850

Term of patent 14 years

Int. Cl. D7—99

U.S. Cl. D44—10

FIG. 1

FIG. 2

FIG. 3

FIG. 4

FIG. 5

I claim:

The ornamental design for a combined coaster and ash tray, as shown.
